UNITED STATES PATENT OFFICE.

ROBERT C. RUSSELL, OF PITTSBURGH, PENNSYLVANIA.

INDEX.

Application filed September 26, 1921. Serial No. 503,287.

To all whom it may concern:

Be it known that I, ROBERT C. RUSSELL, a citizen of the United States, and a resident of Pittsburgh, in the county of Allegheny and State of Pennsylvania, have invented 5 certain new and useful Improvements in Indexes; and I do hereby declare the following to be a full, clear, and exact description of the invention, such as will enable 10 others skilled in the art to which it app pertains to make and use the same.

This invention relates to improvements 15 in indexes and has particular reference to those indexes which are adaptable for use in the indexing of public records, such as those which relate to transactions in connection with real estate or other property, or records of judgments, etc.

One object of my present invention is 20 to provide an index which shall reduce to a minimum the time and labor of the searcher for a particular name, regardless of the fact that the name being searched may be spelled in two or more different 25 ways.

A further object is to provide an index 30 of the character specified which shall be flexible, and which shall include an element having such arrangement of sur-name key letter designations and given name designations that, when considered together shall be so indicated by numerals on said element as to enable the searcher quickly and accurately 35 to locate the place in the record where transactions under the particular name being searched are entered.

With these and other objects in view the 40 invention consists in certain novel features as hereinafter set forth and pointed out in the claims.

In the accompanying drawings; Figure 1 is a view of a table or element to be so associated with groups or section of leaves 45 of a record constituting the body of the index, and Figure 2 is a view illustrating one of the pages of the index.

In the drawing I have illustrated and will hereinafter describe the application of my 50 invention to a "judgment docket" but it will be understood that my improvements are applicable for indexing deeds of transfer of property and other public records.

A table or element 1 is placed in and forms an essential part of the index,—said

table or element being preferably placed 55 at the front of the index.

The index is divided into a plurality of sections each having a designating number, and each section comprises a plurality of pages which are numbered consecutively and 60 the section number appears on each page of a section. For example, Figure 2 of the drawing shows page "1" of section "915," and the page here represented is from an index book in which sur-names having the 65 initial letter "S" and given names having the initial letter "I" or "J."

The index as a whole may be subdivided as the size of the index in a given case may require and for the initial letters which 70 most frequently occur in names, several books for each such initial letter may be provided, and each book made to contain certain selected given names.

The page shown in Figure 2 (which is 75 page 1 of a section of pages) is divided by a horizontal line 2 and vertical lines 3 to form a plurality of short vertical columns 4, at the upper portion of the page, for a purpose which will be hereinafter explained. The pages of the index are arranged to receive the names of persons interested in transactions and data relating thereto. The page represented in Figure 2 of the drawing is designated to receive 80 the names of defendants and plaintiffs and various data relating to judgments to which 85 they were parties.

The table or element shown in Figure 1 90 of the drawings, embodies a block of vertical columns *c* to *t* designated at the tops by letters representing given name initial letters. In the table or element shown, the vertical columns *c* to *j* are designated at 95 the tops by the letters "A" to "H" inclusive, the column *k* by the letters "I J"; the column *l* by the letters "K L"; the column *m* by the letter "M"; the column "n" by the letters "N O"; the column *o* by the letters "P Q"; the column *p* by the letter "R" the column *q* by the letter "S"; the column *r* by the letters "T U V"; the column *s* by the letters "W X Y Z" and the column *t* by the letters "Corp. etc."

Over the row of given name initial letters, the designation "Given name initials and section numbers" appears.

The table 1 is provided at one side with

5 a vertical column *u* designated at its top to contain "key-letters," and the table is divided by a plurality of horizontal lines whereby numerous blocks are formed in 6 horizontal alignment with key letters in the column *u* and in vertical alignment with the given name letters, to contain section numbers.

In the vertical column *u*, "L," "M," "N," 10 "R," "T" and combinations of these key letters are located, and at the bottom of said column *u*, the abbreviation "Misc." appears.

In order that the index may be subdivided and the search for particular names 15 shortened, combinations of each of the key letters are provided. Thus, below the key letter "L," the key letters "M," "N," "R," "T," are combined therewith, and in a similar manner, each of the key letters has combined therewith, the other key letters.

Names will be indexed according to the key letters first occurring after the initial letter of the name and the index entry will be made in a book or set of cards devoted to 25 names beginning with the initial letter of the name. Where a name contains, two or more key letters, it will be indexed according to the two key letters first occurring after the sur-name initial. Thus, the name 30 "Small," would be indexed, according to the key letter combination or subdivision "M L," while the name "Sims" would be indexed according to the key letter "M."

The several given name designations in the horizontal row near the top of the table are given numerical equivalents beginning 40 with "1," and in the illustration in Figure 1 of the drawing, these numerical equivalents extend from "1" to "18," the latter being the numerical equivalent of the designation "Corps, etc."

The key letters L, M, N, R, T, are also given numerical equivalents 1, 2, 3, 4, 5 respectively and the numerical equivalent of 45 "Misc" is "6." The combination of key letters are also given numerical equivalents which contain figures representing the numerical equivalents of the two key letters which may be combined. The numbers in 50 the blocks of the table or element 1 refer to sections in the index and each of said numbers a combination of the numerical equivalent of a given name and a key letter or key letters numerical equivalent.

55 The arrangement of the numerical equivalents may conveniently be computed as follows:—

The numerical equivalents of the given name initial may be considered as units 60 (A = 1, B = 2, etc.). The key letters may then be considered as having numerical equivalents as follows:—viz L = .1, M = .2, N = .3, R = .4, T = .5, Misc. = .6,—or L = .10, M = .20, etc. In placing 65 any one of the key letters in a secondary

position, its numerical equivalent becomes one-tenth of its former numerical equivalent. Thus L, (in a secondary position) equals .01, M (secondary) = .02, etc. Therefore L M = .10+.02=.12 or combined with 70 the numerical equivalent of the given name initial "A," the result would be 1.12. On the table or element 1, however, we would represent this as 112, omitting the decimal point, and so also with respect to the various section numbers on the table. 75

To locate a name in the index, the searcher will associate the numerical equivalent of a given name initial with the numerical equivalent of a key letter or combination 80 of key letters and the associated numerals will represent the number of the page on which the name being searched may be found. For example, if the name J. H. Shelton is being searched, the searcher, finding 85 that the name contains two key letters,—l and t,—and that the given name initial is "J," he will find that the number in the vertical column *k* in horizontal alignment with the key letters "L T" is 915, and this 90 number indicates the section in the index in which the name may be found, as indicated in Figure 2 of the drawing.

It frequently happens that the record being indexed contains many transactions by 95 parties of certain names (although sometimes they may be different spelled) and it is desirable that these names be brought together in a separate section of the index where they will be entered along with data 100 relating thereto. In such cases, the names and the numbers of the separate sections in which the names are indexed will be entered in one or another of the columns 4 near the top of an index page. For example, if 105 the name "John Slater" is being searched, the searcher will locate the number of the section on the table as 915, the same as when searching the name "J. H. Shelton," but upon reference to this section, he will 110 find that the name "Slater" is indexed in separate section 2010 of the index.

Having fully described my invention what I claim as new and desire to secure by Letters Patent, is:—

1. An index comprising a series of sections each section comprising a plurality of consecutively numbered pages, the pages in any one section bearing the same section number which is different from any other section number, and said pages designated to contain sur-names and other data, and an element having a series of given-name initial letters having numerical equivalents, said element also having thereon a series of sur-name key letters *l*, *m*, *n*, *r*, *t* and combinations of each of said key letters with each of the others, each of said key letters having a numerical equivalent and the combined key letters having combined numerical equivalents. 125

- lents, the association of the given-name numerical equivalents with the numerical equivalents of the key letters or combinations of key letters forming numbers on said element representing numbers of sections where names being searched may be found.
2. An index comprising a series of sections each section comprising a plurality of consecutively numbered pages, the pages in any one section bearing the same section number which is different from any other section number, and said pages designated to contain sur-names and other data, and an element having a series of given-name initial letters having numerical equivalents, said element also having thereon a series of sur-name key letters *l, m, n, r, t* and combinations of each of said key letters with each of the others, each of said key letters having a numerical equivalent and the combined key letters having combined numerical equivalents, the association of the given-name numerical equivalents with the numerical equivalents of the key letters or combinations of key letters forming numbers on said element representing numbers of sections where names being searched may be found, the first page of each section of pages being divided and a portion designated to receive frequently occurring names and section numbers referring to sections in which such names are separately indexed together with data relating thereto.
3. An index comprising a series of sections designated to contain sur-names and other data, and an element having thereon a series of given name initial letters having numerical equivalents and a series of sur-name key letters *l m n r t*, and combinations of each of said key letters with the others, each of said key letters having a certain numerical equivalent when used alone, and each key letter having a numerical equivalent equal to a decimal part of its original equivalent, when associated in a secondary position with another key letter, the association of the given name numerical equivalents with the numerical equivalents of the key letters and combinations of key letters forming numbers on said element representing numbers of sections where names being searched may be found.
- In testimony whereof, I have signed this specification in the presence of two subscribing witnesses.
